OUTLET BOX SUPPORT AND METHOD OF USING THE SAME

Filed June 4, 1928

John Bernet

Charles H. Hills Attn:

UNITED STATES PATENT OFFICE

JOHN BERNET, OF CHICAGO, ILLINOIS

OUTLET-BOX SUPPORT AND METHOD OF USING THE SAME

Application filed June 4, 1928. Serial No. 282,655.

This invention relates to improvements in outlet box supports, and more particularly to supports especially desirable for mounting an outlet box or the like upon a brittle wall, such as wall-board, marble and the like, and the invention also relates to an improved method for mounting boxes upon such walls, although the means disclosed herein are adaptable for mounting various articles on various surfaces, as will be apparent to one skilled in the art.

In the past, when outlet boxes and the like have been mounted on substantially hard and brittle walls, it has been customary to provide an aperture in the wall in which to set the box and then drill smaller apertures or recesses in the wall to accommodate the expansion bolts which pass through the mounting bracket which is usually standard equipment on outlet boxes for this purpose. The expansion bolts and other means heretofore used for this purpose have in most cases proven objectionable in that they tend to break the brittle wall adjacent the larger aperture in which the box sets, thereby rendering a durable mounting of the box impossible without the employment of additional labor and extraneous means. Further with these formerly known means, especially with expansion bolts, experienced operators were necessary to properly secure the means without breaking the margin of the wall, and even with such operators the margin was frequently broken.

The present invention is designed to overcome the above noted defects and objections in the provision of an outlet box support which is easily and readily, though none the less firmly, secured to a hard and brittle wall without the necessity of employing an expert operator.

The invention also seeks to provide means for securing an outlet box to a brittle wall, which means eliminate substantially all possibility of breaking or cracking the margin of the wall.

A further object of the present invention is the provision of means for mounting an outlet box to a hard or brittle wall in a simple and easy manner without necessitating the

employment of any additional tools or instruments.

A still further object of the present invention is to provide means for mounting an outlet box to a wall, which means are provided with gauging elements whereby they may be readily seated in proper position.

Still a further object of the present invention is to provide an improved method of mounting an outlet box to a hard or brittle wall.

While some of the more salient features, characteristics and advantages of devices embodying the present invention have been above pointed out, others will become apparent from the following disclosures.

The invention includes these and other features of construction and combinations of parts hereinafter described and shown in the preferred form in the drawings, as more particularly indicated by the claims.

On the drawings:

Figure 1 is a fragmentary sectional view of a wall showing an outlet box mounted thereon by means embodying principles of the present invention;

Figure 2 is an enlarged transverse sectional view taken substantially as indicated by line II—II of Fig. 1;

Figure 3 is an enlarged fragmentary view in elevation taken from the left of Fig. 2;

Figure 4 is a view similar to Fig. 3 taken from the right of Fig. 2;

Figure 5 is a fragmentary transverse sectional view, with parts omitted, taken substantially along line V—V of Fig. 3;

Figure 6 is a fragmentary sectional view, with the outlet box omitted, taken substantially along the staggered line VI—VI of Fig. 3; and

Figure 7 is an enlarged sectional view taken substantially along line VII—VII of Fig. 3.

As shown in the drawings: At the outset, it is to be distinctly understood that though the illustrated embodiment of the present invention is shown as securing an outlet box to a wall, the same is equally adaptable for securing other and various articles to any

form of a surface such as walls, a ceiling, side, etc.

Further it is to be understood that although the term outlet-box is used herein and in the appended claims, the same is to be construed to mean an outlet box, switch box, terminal box or any desired article of similar character or shape.

The structure arbitrarily selected to sufficiently disclose the illustrated embodiment of the present invention comprises a wall including studs or joists 1 to which is secured a panel 2 of wall board or similar material, in most instances hard and brittle. An outlet box 3 of standard construction is seated in the aperture 4 provided in the panel or wall 2 for this purpose and is secured to the adjacent margins of the wall by mounting brackets 5 and improved means embodying the present invention. The mounting brackets 5 are customarily provided as standard equipment with the outlet box 3 and are secured thereto in any desired manner, as indicated by the stud screws 6.

Since both ends of the box are secured to the wall in identical manner, the securing means at one end only will be described herein.

In mounting the box it is customary to drill the wall so as to provide a pair of spaced apertures therethrough which are sufficiently spaced from the edge of the wall to eliminate the possibility of the wall margin cracking or chipping off. The bracket 5 on the box 3 is also provided with a pair of spaced apertures and when properly positioned the apertures in the bracket will be directly in alignment with those in the wall. To firmly secure the box to the wall without the employment of expansion bolts or similar means, a novel clip is provided which comprises a body portion 7 for engagement with the opposite face of the wall, which body portion is provided with a plurality of tongues 8, in this instance two, bendable so as to embrace the edge of the wall and overlie the front surface thereof adjacent the bracket 5, whereby the clip is temporarily secured in position. The body portion 7 is also provided with a pair of tongues 9 extending towards the box, and which may or may not abut the box, but which in any event effectively provide gauging means for the quick positioning of the clip in such a manner that a pair of apertures in the body portion 7 thereof will fall in alignment with the apertures through the wall and bracket 5. Through these apertures securing means, in this instance stud screws 10, are secured, the screws engaging both the bracket 5 and wall 2, and threadedly engaging the body portion 7 of the clip.

The spaced apertures in the body portion 7 of the clip are preferably punched therein simultaneously with the forming of the clip,

one operation only being required to form the clip and provide the apertures therein. By punching the apertures, a burr 11 results on the under-side of the body portion 7, which burr provides sufficient metal for the tapping of several threads therein, the tapping operation being the second and final operation in the formation of the clip. It is to be understood, however, that if so desired metal of sufficient softness for the stud screws 10 to effectively tap the same at the time of entering thereinto may be used, thereby dispensing with the previous operation of tapping the apertures in the body portion.

A preferred method of mounting the outlet box in the wall 2 consists of first providing the large aperture 4 in the wall, and then drilling the smaller apertures in the wall margin, after which the clip is mounted in the position shown by the full lines in Figure 6. The tongues 8 of the clip are then bent downwardly as indicated by the dotted lines in Figure 6.

The outlet box itself is next inserted in the aperture 4 with the bracket 5 overlying the front face of the wall adjacent the extremities of the tongues 8. When the box is so positioned, the gauging tongues 9 on the clip will be in such close proximity to the box that the clip will assume a position with the apertures therein in alignment with those through the wall and bracket 5, whereby the stud screws 10 may be easily inserted and threadedly engaged with the body portion 7 of the clip. Obviously no marked skill or experience is necessary to so mount the outlet box, and the same will be secured to the wall in a firm and positive manner with no danger of breaking or cracking the margin of the wall.

From the foregoing it is apparent that I have provided novel means for mounting an outlet box to a hard and brittle wall, which means are exceedingly easy to manipulate, embodying little labor and material, are durable and substantial, and may be economically manufactured.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In combination, an outlet box having a bracket for engagement with one face of the margin of a wall adjacent an aperture therein in which said box seats, and a clip including a substantially flat portion for engagement with the opposite face of said margin, tongues on said portion bendable around the edge of said wall, and securing means pass-

ing through said wall and engaging both said bracket and clip.

2. In combination, a wall having an aperture therein, an outlet box mountable in said aperture, a bracket on said box engageable with a face of said wall, and a clip including a body portion engageable with the opposite face of said wall, and tongues on said clip bendable around the edge of said wall, said body portion being apertured to receive securing means connected to said bracket and passing through said wall.

3. In combination, an outlet box having a mounting bracket thereon for engagement with one face of a wall adjacent an aperture therein, and a clip including a body portion engageable with the opposite face of said wall, means on said clip for embracing the edge of said wall, and securing means connected to said bracket and said clip.

4. In combination, a wall having a relatively large aperture therein and relatively small apertures adjacent thereto, an outlet box mountable in said large aperture, a bracket on said box having apertures therein for alignment with said small aperture, a clip having apertures therein and engageable with an opposite face of said wall, means on said clip for embracing the edge of said wall, means on said clip extending towards said box for gauging the position of said clip so the apertures therein will fall in alignment with the small apertures in said wall, and securing means passable through said apertures.

5. In combination, a wall having an aperture therein, an article equipped with means to engage a face of said wall, said means having an aperture therein alignable with the aperture in said wall, apertured means engageable with the opposite face of said wall, means on said last mentioned means for gauging the position of the same so the aperture therein will be in alignment with the aperture in said wall, and securing means engageable in all of said apertures for attaching said article to said wall.

6. As an article of manufacture, a clip including a substantially flat plate, and a tongue extending at an angle to one edge of the plate and adapted for bending over the edge of a support, said plate being apertured to receive securing means passing through said support, and said securing means also engaging an article to be secured to said support.

7. As an article of manufacture, a clip including a substantially flat plate, a tongue extending normal to one edge of the plate and adapted for bending over the edge of a support, said plate being adapted to receive securing means passing through said support and engaging an article to be secured to the support, and means connected to said plate

for gauging the position of said clip relative to said article.

8. As an article of manufacture, a clip including a substantially flat plate, a tongue extending normal to an edge of the plate and adapted for bending over the edge of a support, said plate being adapted to receive securing means passing through said support and engaging an article to be secured to the support, and a tongue extending in the plane of said plate for gauging the position of said clip relative to said article.

In testimony whereof I have hereunto subscribed my name at Chicago, Cook County, Illinois.

JOHN BERNET.
